UNITED STATES PATENT OFFICE.

DANIEL O'BRIEN, OF WASHINGTON, DISTRICT OF COLUMBIA.

DESIGN FOR A SHIRT-CUFF.

SPECIFICATION forming part of Design No. 18,343, dated May 22, 1888.

Application filed April 3, 1888. Serial No. 269,517. Term of patent 3½ years.

To all whom it may concern:

Be it known that I, DANIEL O'BRIEN, a citizen of the United States, residing at Washington, in the District of Columbia, have invented 5 a certain new and original Design for Cuffs; and I do hereby declare the following to be a full, clear, and exact description of the invention, such as will enable others skilled in the art to which it appertains to make and use 10 the same.

This design is for cuffs or wristbands; and it consists in a cuff or wristband having the shape of a truncated cone, as clearly shown in the accompanying drawing.

15 A represents a cuff of the form of a truncated cone, and B the seam.

At or near the lower edge or smaller end of the cuff a button-hole is made on the side thereof, as shown, in which a cuff-button may

be inserted to give the cuff an ornamental and 20 finished appearance.

At the smaller end of the cuffs the inner edges are turned over, as shown at C, so that the sides *aa* are substantially in a straight line or sight-line.

25 What I desire to claim is—

The design for a cuff, consisting of a body of truncated form having the inner corners of the smaller end turned in V shape, and so that the inside edges thereof form a right line, substantially as shown and described.

30 In testimony whereof I affix my signature in presence of two witnesses.

DANIEL O'BRIEN.
